Inventor

George H. Brinkley

UNITED STATES PATENT OFFICE

GEORGE H. BRINKLEY, OF BALTIMORE, MARYLAND

NECKTIE OF THE FOUR-IN-HAND TYPE

Application filed May 5, 1931. Serial No. 535,113.

My invention relates to improvements in neckties of the four-in-hand type and has for its primary object to provide an article of this character which will simulate a hand tied necktie and yet is easier to put on and take-off and will not wrinkle.

A further object of the invention is to provide a necktie of the above-mentioned character having means for clamping the tie in its adjusted position.

Another object of the invention is to provide a necktie of the above-mentioned character which is simple and durable in construction, reliable and efficient in use and inexpensive to manufacture.

Other objects and advantages of the invention will be apparent during the course of the following description.

In the accompanying drawings, forming a part of this specification and in which like numerals are employed to designate like parts throughout the same,

Fig. 1 is a front elevation view of the tie,

Fig. 2 is a section taken on lines 2—2 of Fig. 1,

Fig. 3 is a section taken on lines 3—3 of Fig. 2,

Fig. 4 is a rear view of the noose segment, and,

Fig. 5 is a cross section taken on lines 5—5 of Fig. 2.

In the drawings, wherein for the purpose of illustration, I have shown a preferred embodiment of my invention, the numeral 5 denotes the noose segment which is formed from

a sheet of metal tapering downwardly and having its end portions curved backwardly. The outer face of the segment 5 is entirely covered by a piece of cloth material 6, corresponding to the material of the tie, the ends of the material being folded around the side edges of the segment, as at 7, and secured thereto. The tie consists of two strips 8 and 9, the strip 8 having its small end inserted in the top of the segment 5 and fixedly secured between the front wall of the segment and clamping member 10, by the rivet 11. The small end of the strip 9 extends up the front face of the segment 5, beneath the cloth material 6, and is folded over the upper edge of

the segment. Attached to the extremity of the small end of the strip 9 is an elastic strip 12, which extends down through the tubular clamping wedge 13, terminating a short distance below the lower end of the segment. The wide end of the strip 8 extends down through the segment being disposed between the clamping member 10 and wedge 13. The wedge 13 is fixedly secured to the elastic strip 12, by the rivet 14 and through the resiliency of the strip 12 clamps the tie strip 8 against the clamping member 10, holding it in its adjusted position.

In use, it will be seen that by constructing the necktie in accordance with the foregoing it will be identical in appearance with a hand tied tie. By pulling on the wide end of the strip 8, the noose segment 5 may be properly adjusted with respect to the collar, and when adjusted will be held in position through the action of the clamping wedge 13 which co-acts with the clamping member 10 to clamp the strip 8 in position. Upon pulling the free end of the elastic strip 12, the wedge 13 may be released from clamping engagement with the strip 8, when desired.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. A necktie of the character described comprising a noose segment formed from a sheet of metal having its end portions curved backwardly, a narrow tie strip, a wide tie strip extending up the front face of the segment and folded over the upper edge thereof, a clamping member securing the small end of the narrow tie strip to the inside of the front wall of the segment, the opposite end of the narrow tie strip extending down through the noose segment, and a wedge clamp secured to the upper end of the wide tie strip within the noose segment, adapted to co-act with said clamping member to secure the narrow tie strip in its adjusted position.

2. A necktie of the character described comprising a noose segment formed from a sheet of metal having its end portions curved backwardly, a narrow tie strip, a wide tie strip having its small end folded over the upper edge of the noose segment, a clamping member securing the small end of the narrow tie strip to the inner front wall of the noose segment the opposite end of said narrow strip extending through the noose segment and a wedge clamp resiliently supported in said noose segment, adapted to co-act with said clamping member to secure the narrow tie strip in its adjusted position.
3. A necktie of the character described comprising a noose segment of substantially tubular form, a narrow tie strip, a wide tie strip having its small end folded over the upper edge of the noose segment, a clamping member securing the small end of the narrow tie strip to the inner front wall of the noose segment, the opposite end of the narrow strip extending through said noose segment and a wedge clamp secured to the upper end of the wide tie strip within said noose segment, adapted to co-act with said clamping member to secure the narrow tie strip in its adjusted position.
4. A necktie of the character described comprising a noose segment of substantially tubular form, a narrow tie strip, a wide tie strip having its small end folded over the upper edge of the noose segment, a clamping member securing the small end of the narrow tie strip to the inner front wall of the noose segment, the opposite end of the narrow strip extending through said noose segment, a wedge clamp disposed within said noose segment, and an elastic strip suspending said wedge clamp from the upper end of the wide tie strip, adapted to hold the wedge clamp in clamping engagement with the narrow tie strip.

In testimony whereof I affix my signature.
GEORGE H. BRINKLEY.
